UNITED STATES PATENT OFFICE.

CHARLES D. SLOCUM, OF TOPEKA, KANSAS.

DESIGN FOR A SMOKER'S STAND.

60,967.

Specification for Design.

Patented May 16, 1922.

Application filed February 3, 1921. Serial No. 442,311. Term of patent 3½ years.

To all whom it may concern:

Be it known that I, CHARLES D. SLOCUM, a citizen of the United States, residing at Topeka, in the county of Shawnee and State of Kansas, have invented a new, original, and ornamental Design for Smoker's Stands, of which the following is a specification, reference being had to the accompanying drawing, forming part thereof.

Figure 1 is a front elevation, Fig. 2 is a side elevation, and Fig. 3 is a top plan view, of a smoker's stand, showing my new design.

I claim:

The ornamental design for a smoker's stand, as shown.

CHARLES D. SLOCUM.
